UNITED STATES PATENT OFFICE.

HENRY FLICK, OF JACKSON, MICHIGAN, ASSIGNEE TO HAYES WHEEL COMPANY, OF JACKSON, MICHIGAN.

AUTOMATIC SPOKE-TURNING MACHINE.

Application filed October 4, 1921. Serial No. 505,241.

To all whom it may concern:

Be it known that I, HENRY FLICK, a citizen of the United States, residing in the city and county of Jackson, State of Michigan, have invented certain new and useful Improvements in Automatic Spoke-Turning Machines, of which the following is a specification.

This invention relates to an improved 10 automatic spoke turning machine. The objects of the invention are:

First, to provide such a machine which will from a previously prepared spoke billet turn out a complete finished spoke with a 15 tapered head and the tenon finished.

Second, to provide such a structure with an improved arrangement of cutter heads.

Third, to provide in such a structure an 20 improved means for effectively turning the entire spoke.

Fourth, to provide in such an automatic machine an improved sander means.

Further objects and objects relating to 25 details and economies of construction and operation will definitely appear from the detailed description to follow.

The objects of the invention are accomplished by the devices and means described 30 in the following specification. The invention is clearly defined and pointed out in the claims.

A structure showing a preferred embodiment of the invention is illustrated in the accompanying drawing, forming a part of 35 this specification, in which:

Fig. I is a side elevation of the improved machine from the right side showing the arrangement of driving pulleys, sand belt 40 tightener and the like.

Fig. II is a detail end elevation view on a reduced scale from the left end of Fig. I, the main driving belt being omitted.

Fig. III is a detail sectional elevation view, certain parts being shown in full lines, 45 taken on the irregular line 3-3 of Figs. I, V and IX, showing the multiple revolving work supporting means with the cutter heads and sander belt omitted.

Fig. IV is a detail sectional view on irregular line 4-4 of Figs. II and III, on the same scale as Fig. III, showing a series of 50 spokes in process of manufacture and successive action of the cutter heads and sanding belt, other portions being omitted.

Fig. V is an enlarged detail sectional view

on the irregular line 5-5 of Figs. II and III, showing details of the driving gears, both for revolving the multiple head work holder and revolving the live spindles of the lathe.

Fig. VI is a detail sectional view on line 6-6 of Figs. I and VII, showing details of the sander belt tightener and drive.

Fig. VII is a detail sectional elevation on the irregular line 7-7 of Fig. VI, showing the method of adjusting and maintaining the tension and the position of both the driving and sander belts.

Fig. VIII is an enlarged detail radial sectional view through the spring clamp and cam actuating means of the tail center spindle for each spoke, taken on line 8-8 of Figs. I and IV.

Fig. IX is an enlarged detail sectional view of the worm driving gear means for 75 revolving the multiple work carrier, taken on line 9-9 of Figs. II and III.

In the drawings similar reference numerals refer to similar parts throughout the several views and the sectional views are 80 taken looking in the direction of the little arrows at the ends of the section lines.

Considering the numbered parts of the drawing by their numbers, 1 is the base on which the other parts of the machine are mounted. 2 and 3 are the general end plates of the main frame of the machine which support and carry the other parts. A general supporting case 4 is provided to embrace the central upper part of the side 85 frame 2 and a similar supporting circular plate 5 is at the other end of the machine.

The main supporting shaft 6 is carried in a bearing 7 at the center of the plate 5 and bearing 8 at the center of plate 4. A cylindrical shell 9 is provided at the center to which at the left end is secured the head 10 and a supporting plate 11 is parallel therewith and secured thereto by an outer shell 11'. This constitutes the holder of 100 the multiple lathe spindle heads or headstock, the same being revolubly supported on the shaft 6. A similar head 12 is at the opposite end of the cylindrical shell 9 and carries the tail spindles or centers.

The headstocks each comprise a spindle 13 carrying a head 14 which is provided with a thrust bearing 15 between it and the plate 10. The same is held securely against the thrust bearing 15 by the coiled spring 16. 110

Upon the head 17 at the outer end of the spindle 13 is a chuck comprising a pair of rollers 18 transverse to the center forming the jaws for receiving the tapered or mitered hub end of a spoke. The spindle is provided with a pinion 19 and is driven by a gear 20 keyed to the shaft 6 at 21, the gear 20 serving to drive all of the multiple spindles at the same time.

10 The tailstock comprises the sleeve 22 (see Figs. III and VIII) carrying the reciprocating center 23 which is secured against rotation. The sleeve is clamped securely by clamp 24. A bushing 25 is provided for the outer end of the reciprocating member which is held pressed inwardly by the coiled spring 27. Each tailstock is provided with a roller 25' which bears against the spring pressed ring 28 which is supported by a series of pins 29 having coiled springs 30 disposed thereon within the circular plate 4.

A cam 31 (seen in dotted lines in Figs. III and IV and in full lines in Fig. VIII) is provided for withdrawing the tailstock 25 from engagement with the finished spokes to permit their discharge and to allow the same to snap into engagement with the spoke billets at the right time. These tail centers are round and fixed so that as the spokes revolve the centers penetrate the ends of the same and hold them very securely, a matter of special importance in the sanding operation.

35 32 is the magazine for receiving the spoke billets 33. These are carried from the magazine at the opening 34 by being shucked and swung under the cutter heads, as indicated at 35, rotating on the lathe centers as they progress and being acted upon by the cutter heads.

The multiple lathe spindles of the machine are driven by the pulley 36 which is driven by the belt 37. The pulley 36 is on the shaft 38 which bears a worm 39 which drives a worm gear 40 on shaft 41 which drives pinion 42 which meshes with pinion 43 on the main shaft 6 which, therefore, drives the main shaft 6 at a relatively low rate of speed and revolves the spindles at a 45 relatively slow speed as they are advanced to the cutter heads and sander. The work carrier is revolved on its axis from shaft 6.

50 Secured to shaft 6 is a gear 44 which drives a train of gears 45, 46 and 47. The gear 47 meshes with gear rim 48 (see Figs. III and V) which revolves the multiple lathe work carrier upon its axis around the shaft 6. This causes the multiple lathe to revolve around its center while the lathe spindles are being revolved on their centers as they are advanced.

55 The cutter head 49 is provided with blades 49' having curved end portions 50 corresponding to the curve at the inner end 60 of a spoke, so that when a spoke swings to

position, as indicated in Fig. IV, by the first round spoke 35, the cutter very quickly reduces it to size while the revolving spoke is passing.

The cutter head 49 is carried on the shaft 70 51 which is supported in suitable shouldered bearings 52, 53 to maintain the same against longitudinal displacement. These are driven by pulley 54. The pulley 55 at the outer end of the shaft drives the pulley 36 through 75 the belt 37.

Between the blades 49 of the cutter head are disposed angularly projecting saw like cutters 49'' very like the sections of a dado saw, which cut a neck or annulus towards 80 the outer end of the spoke, thus forming the spoke tenon. Further on, on the frame, is supported the cutter head 59 which is carried on the shaft 58 which is provided with a pulley 57. An idler pulley 56 is provided 85 on the frame between the pulleys 54 and 57. Around these is disposed the driving belt 60. The cutter head 59 is provided with twice the number of knives as the cutter head 49 and it works very rapidly and gives 90 a smooth finishing cut to the spoke.

Sander rolls 61 and 62 are supported in proximity to the path of the spindles beyond the cutter heads on suitable axes in the frame. The roll 62 is carried on arm 95 63 pivoted at 64 for adjusting the same. A hand wheel 65 is provided for adjusting the same laterally.

The sander rolls conform in their longitudinal outline to the contour of the cutter heads (see Fig. II). The sander belt 66 is driven from the roll 67, the same being provided with a pulley 68 driven by the belt 69 by any suitable means. The pulley is carried on the adjustably pivoted standard 70 on trunnion 71.

On a suitable base 72, adjustable by the hand screw 73 in threaded lug 74, is the tension weight structure 75 connected by pivot 76 through rod 77 by the adjustable nut 78 to the said pivotal standard 70.

In the operation of the machine, spoke billets 33 are placed in the magazine 32 and, when the machine is put in motion, the first pair of spindles that come opposite the bottom billet in the magazine is snapped very strongly by the tailstock into and between the double roller chuck 18, 18, and is advanced revolving on its own axis to the cutter head 49 which rough cuts the main body of the spoke in its exact and proper relation to the tapered chucked end. The dado saws 49' cut an annular groove forming the tenon of the spoke with a projecting piece of wood beyond the same (see illustration in the lower part of Fig. III).

The revolving spoke is then advanced to the cutter 59 which, owing to the fact that it has double the number of knives, cuts a very smooth finishing cut straight across 130

the outer body and the button-like projection at the end. The spoke then advances to the rapidly traveling sander belt 66 which is held yieldingly in contact with the turned body of the spoke, finishing the same, and after this sanding operation the roller 28 on the tail stock passes into engagement with the cam 31 which gradually withdraws the tail center to the position indicated in Fig. VIII, and drops the spoke with the button on the end of the tenon, which can be thereafter cut off. The roller continues upon the cam until the tail spindle comes opposite the next succeeding billet in the magazine when the process is repeated. A cut-off saw for the tenon may be provided in this connection.

This structure can be greatly modified without departing from the invention. A multiple structure is shown. The spokes could be turned and finished without forming the tenons and on the other hand the tenons might be formed without the final finishing process, all to the advantage to the extent indicated. A lathe with a single spindle and pair of rollers to properly dispose the cutting head could be made use of to make the spokes, and the dado saw for cutting the annular grooves could be made use of independent of the cutter. It is desired to claim the invention specifically and also broadly, as pointed out in the appended claims.

Having thus described the invention what I claim and desire to secure by Letters Patent is:

1. The combination with a multiple spindle spoke lathe, of chucks for the spindles thereof comprising opposite and transversely disposed rollers, spring means for pressing the tail centers against the billets, a cam for withdrawing the same and releasing the tail centers for automatically spearing the ends of the spokes, a rotary cutter for rough cutting the spokes as they are swung past the same, dado saws carried by the said cutter between the blades for forming the tenon end of the spoke, a finishing cutter head with a large number of cutters for giving the spoke a finishing cut, and a sander belt disposed on suitably conformed rolls corresponding to the spoke for sanding the same, all coacting as specified.

2. The combination with a multiple spindle spoke lathe of chucks for the spindles thereof comprising opposite and transversely disposed rollers, spring means for pressing the tail centers against the billets, a cam for withdrawing the same and releasing the tail centers for automatically spearing the ends of the spokes, a rotary cutter for rough cutting the spokes as they are swung past the same, dado saws carried by the said cutter between the blades for forming the tenon end of the spoke, and a finish-

ing cutter head with a large number of cutters for giving the spoke a finishing cut, all coacting as specified.

3. The combination with a multiple spindle spoke lathe, of chucks for the spindles thereof comprising opposite and transversely disposed rollers, spring means for pressing the tail centers against the billets, a cam for withdrawing the same and releasing the tail centers for automatically spearing the ends of the spokes, a rotary cutter for rough cutting the spokes as they are swung past the same, dado saws carried by the said cutter between the blades for forming the tenon end of the spoke, and a sander belt disposed on suitably conformed rolls corresponding to the spoke for sanding the same, all coacting as specified.

4. The combination with a multiple spindle spoke lathe, of chucks for the spindles thereof comprising opposite and transversely disposed rollers, spring means for pressing the tail centers against the billets, a cam for withdrawing the same and releasing the tail centers for automatically spearing the ends of the spokes, a rotary cutter for rough cutting the spokes as they are swung past the same, and dado saws carried by the said cutter between the blades for forming the tenon end of the spoke, all coacting as specified.

5. A spoke lathe comprising a rotary chuck having a pair of spaced, parallel rollers adapted to receive the tapered end of a spoke and locate the same lengthwise by its engagement with the inclined faces of the taper, a tail center and means for advancing the same to engage the tenon end of the spoke and force the tapered end between the rollers to the desired location, in combination with a cutting means for shaping the spoke, including the tenon end, and means for causing said spoke and cutting means to approach one towards the other laterally of the spoke.

6. A many spindled spoke lathe comprising a series of rotary chucks each comprising a pair of spaced rotary rollers between which the tapered end of the spoke may be advanced and by which it may be rotated, a corresponding series of centers, each in alignment with a chuck, and means for advancing said centers to locate the tapered end of each spoke between the rollers, a cutting instrumentality for shaping the spokes including the tenons, and means for moving the series of chucks and centers to bring them in succession laterally towards the cutting means.

7. The combination in a many spindle spoke lathe of a series of rotary chucks for receiving and rotating spokes, a corresponding series of centers each in alignment with a chuck, with means for advancing said centers to engage the spokes and rotate the

same, a rotary rough cutter for rough-finishing the spokes; a dado saw cutter means disposed to cut an annular groove in the rough-cut spokes for forming the tenon ends 5 of the spokes, a rotary finishing cutter in succeeding relation to said rough cutter and dado saw cutter, and a sanding belt in succeeding relation to said finishing cutter arranged and disposed to act after the said 10 tenon groove has been formed, coacting for the purpose specified.

8. The combination in a many spindle spoke lathe of a series of rotary chucks for receiving and rotating spokes, a corresponding 15 series of centers each in alignment with a chuck, with means for advancing said centers to engage the spokes and rotate the same, a rotary rough cutter for rough-finishing the spokes, a dado saw cutter means disposed to cut an annular groove 20 in the rough-cut spokes for forming the tenon ends of the spokes, and a rotary finishing cutter in succeeding relation to said rough cutter and dado saw cutter, coacting 25 for the purpose specified.

9. The combination in a many spindle

spoke lathe of a series of rotary chucks for receiving and rotating spokes, a corresponding series of centers each in alignment with a chuck, with means for advancing said centers to engage the spokes and rotate the same, a rotary cutter for the spokes, a dado saw cutter means disposed to cut an annular groove in the spokes for forming the tenon ends of the spokes, and a sanding belt in 30 succeeding relation to said finishing cutter arranged and disposed to act after the said tenon groove has been formed, coacting for the purpose specified.

10. The combination in a many spindle 35 spoke lathe of a series of rotary chucks for receiving and rotating spokes, a corresponding series of centers each in alignment with a chuck, with means for advancing said centers to engage the spokes and rotate the same, a rotary cutter for the spokes, and a dado saw cutter means disposed to cut an annular groove in the spokes for forming the tenon ends of the spokes, as specified.

In witness whereof, I have hereunto set 40 my hand and seal.

HENRY FLICK. [L.S.]
